UNITED STATES PATENT OFFICE.

HENRY MONROE, OF SABETHA, KANSAS.

AUTOMATIC RAILWAY-GATE.

1,192,669.

Specification of Letters Patent. Patented July 25, 1916.

Application filed October 30, 1914. Serial No. 869,425.

To all whom it may concern:

Be it known that I, HENRY MONROE, a citizen of the United States, residing at Sabetha, in the county of Nemaha and State of Kansas, have invented certain new and useful Improvements in Automatic Railway-Gates; and I do hereby declare the following to be a full, clear, and exact description of the invention, such as will enable others skilled in the art to which it appertains to make and use the same.

My invention relates to improvements in railway gates of the automatic type which consist of train actuated apparatus for controlling the swinging gates or bars at a railway crossing, to close said gates before the train reaches the crossing and to open the gates after the train has passed the crossing.

The primary object of my invention is to provide novel means for supporting and securing the gate members at the crossing that is attached to the rails and serves to support the gate members in a reliable manner so as to insure their proper operation.

Another object of importance is to provide novel means to be engaged by trains to operate the gates so as to move them into closed and open position.

Another object is to generally improve and simplify railway gates so as to render them more practical, reliable and efficient in operation and inexpensive to install and maintain in operation.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts, Figure 1 is a top plan view of a railroad crossing showing my improved gate attached thereto, Fig. 2 is a longitudinal sectional view showing one of the gate members in side elevation, also the operating mechanism therefor. Fig. 3 is a transverse sectional view showing one of the supporting members for the gate operatively associated with one of the rails of the track, and Fig. 4 is a longitudinal sectional view in detail of a part of the supporting mechanism for the gate, and operating mechanism therefor.

Referring to the drawings, by characters of reference A designates as an entirety a railway crossing, B the rails, C the ties, and D and E balanced gate bars. The gate bars 60 D and E are pivoted as at 1 upon the upper ends of vertical standard 2 and each have secured upon one end a weight member 3 which serves to balance the gate members. An upstanding standard 2 is provided for 65 each of the gate members, said standard and co-operating parts being identical as to construction. An offset apertured boss 4 is formed on one face of each of the standards at the upper end thereof. Pivot bolts or 70 pins 5 are inserted through the gate bars D and E and apertures in the upper end of each of the standards 2 and the apertured bosses 4. Nuts 6 are turned on the threaded ends of said bolts 5, and engage washers 7 75 interposed between the nuts and outer faces of the bosses 4. As a means for limiting the closing movement of the gates to a horizontal position from up position as shown in Fig. 2, I provide a spring clip or supporting member 8 that is secured to each of the standards 2 and limits the movement of the gate member on each standard when said members move into closed position as clearly shown in Fig. 3.

The standards 2 are formed integral with flat elongated metallic base plates 9 at points intermediate and approximately central of the ends of said base plates. The base plates 9 are mounted upon a suitable supporting surface upon the outside of the rails B and extend at right angles to said rails; the inner ends of the base plates 9 are upwardly offset as at 10 so as to engage upon the bases of the rails and formed integral 90 with the offset portions 10 are upstanding flanges 11 which engage the webs of the rails and the ball thereof. Bolts 12 are inserted through the flanges 11 and webs of the rails and have nuts 13 turned on their 100 threaded terminals to secure the bolts in position.

In connection with each standard 2 I provide an upwardly and inwardly inclined brace rod or bar 14 that is provided with angular feet 15 and 16 at its ends, said feet being apertured. The feet 15 and 16 engage respectively the outer end portions of the plates 9 and intermediate portions of the vertical standards 2. Suitable fastening elements 17 serve to secure the feet 15 to the outer end of each of the plates

9. Fastening elements 18 secure the feet 16 to the standard 2.

With reference to the foregoing description it will be observed that I have provided a simple and extremely effective and reliable support for the gate members of a railway gate that will not only act to support the gate members but brace the rails.

An elongated pulley supporting plate 19 provided with a central inverted U-shaped portion 20 is mounted transversely of each of the base plates 9 and receives the base plate in the inverted U-shaped portion 20 thereon. A pair of pulleys 21 is mounted upon each of the plates 19, a pulley being disposed adjacent to each end of said plate, upon the upper face thereof. The plate 19 disposes the pulleys at points on opposite sides of the pivot 1 for the gate members D and E at a point underneath said pivot points.

As a means for automatically operating the gate members D and E, I provide two pairs of pivoted train engaging members or shoes 22 and 23. These pairs of members are arranged upon opposite sides of the crossing A a sufficient distance to permit the gate to close before a train reaches the crossing. Each of the members of the pair 22 consists of a bell crank 24 that is pivoted intermediate its ends as at 25 to a suitable support inside of the track or to one of the rails B and has one arm portion disposed above the level of the rails to be engaged by a train while the other arm portion is disposed below the rail and operatively connected with a pull lever 26 by means of a rod 27 which is pivoted or loosely secured at one end to the lower end of the bell crank 24 and at its other end loosely secured as at 28 to the intermediate portion of the lever 26. Secured to the free end of the lever 26 as at 29 is a cable or some suitable flexible element 30 that is disposed upon the inner side of each of the rails and below the upper surface thereof. Each of the members 30 is passed about a pulley 31 arranged at a point nearly opposite to one of the pulleys 21 and then passed through a suitable aperture in each of the rails and directed at right angles to the rails underneath the pulley. The flexible elements 30 after being passed under the pulleys 21 are directed upwardly on opposite sides of the rail 2 and secured as at 32 to the gate bars D and E. An expansion spring 33 is mounted upon one of the adjacent ties C in connection with each of the bell cranks 24 of the pair 22 and is interposed between the train engaging portion of the bell crank 24 and tie adjacent thereto. These springs 33 normally hold the parts of each of the bell cranks 24 in position to be engaged by a train. Each of the members 23 consists of a bell crank lever, one arm of which is disposed below

the rails and has its lower end connected by means of a rod 27^a, to the lower end of a vertically disposed pull lever 28^a, which is pivotally connected intermediate its ends to the free end of a horizontally disposed bracket 29^a, which is disposed below the top of the rails. Flexible elements 34 are connected to the upper end of the pull levers 28^a and pass over pulleys similar to the ones 31, then the pulleys 21 and to the bars D and E as at 35.

In operation, when a train approaches the members 22, and engages them, they are forced downwardly and a pull communicated to the lever 26 through the rod or connection 27. Assuming that the bars D and E are in up position, as shown in Fig. 2, when a pull is communicated thereto through the flexible elements 30, they will be overbalanced and fall into horizontal and closed position. When the bars D and E descend, the pull on the flexible element 34, located in the rear of the bars D and E, will rock the upper ends of the pull levers 28^a downwardly, causing the lower arms of the bell crank levers 23 to be rocked upwardly, resulting in the upper arms of the bell crank lever 23 being moved above the rails of the track. The spring clips 8 limit the downward movement of the gate bars D and E after the train has passed the crossing A and upon engagement thereof with the members 23, the flexible elements 34 will have a pull communicated thereto and serve to pull the members D and E in up position, as shown in Fig. 2 in the drawings. The gate bars D and E are of the counterbalanced type, so that when in either raised or lowered position, remain in position until operated.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to when required, without sacrificing any of the advantages of my invention, as set forth.

What is claimed is:—

1. A railway gate consisting of a pair of gate bars, upstanding standards, said gate bars being pivoted to the standards intermediate their ends and being balanced relative to said standards, integral base plates carried by the lower ends of the standards and having their inner ends shaped to conform to and arranged to engage the outer faces of the rail at a railway crossing, a transverse pulley supporting bar carried by each of said base plates, pulleys carried on

the ends of said bars and disposed on opposite sides of pivot point of the gate bars, flexible elements secured at their ends on opposite sides of the pivot points of said bars, and directed downwardly under said pulleys and on opposite sides of the gate bars and means to be arranged in advance of the railway crossing on either side thereof to be engaged by a train to communicate 5 a pull to the flexible elements.

2. A railway gate consisting of a pair of gate bars, upstanding standards, said gate bars being pivoted to the standards intermediate their ends and being balanced relative to said standards, integral base plates carried by the lower ends of the standards and having their inner ends shaped to conform to and arranged to engage the outer faces of the rail at a railway crossing, a 15 transverse pulley supporting bar carried by each of said base plates, pulleys carried on 20

the ends of said bars and disposed on opposite sides of pivot point of the gate bars, flexible elements secured at their ends on opposite sides of the pivot points of said bars, and directed downwardly under said pulleys and on opposite sides of the gate bars and means to be arranged in advance of the railway crossing on either side thereof to be engaged by a train to communicate 25 a pull to the flexible elements, said means serving to move the gate bars into and out of closed position, and means to limit the downward movement of the gate bars and support them in closed position. 30

In testimony whereof I affix my signature in presence of two witnesses.

HENRY MONROE.
